UNITED STATES PATENT OFFICE.

GEORGE W. LENTZ, OF CANTON, OHIO, ASSIGNOR TO UNITED ALLOY STEEL CORPORATION, OF CANTON, OHIO, A CORPORATION OF NEW YORK.

SHIRT-METAL-STRAIGHTENING MACHINE.

Application filed January 15, 1923. Serial No. 612,746.

To all whom it may concern:

Be it known that I, GEORGE W. LENTZ, a citizen of the United States, residing at Canton, in the county of Stark and State of Ohio, have invented certain new and useful Improvements in Sheet-Metal-Straightening Machines, of which the following is a specification.

The invention relates to machines for straightening sheet metal, and more particularly for flattening and straightening expanded metal sheets as they are delivered from an expanding machine; and the object of the improvement is to provide means for adjusting the straightening rolls for more effective work on different kinds and conditions of expanded sheets.

The cooperating series of rolls in a straightening machine are usually journaled in bearings in frames which may be adjusted directly to and from each other to vary the extent the peripheries of the rolls of one series protrude toward or into the intervals between the rolls of the other series.

By the present improvement means are provided for adjusting either one or both ends of one bearing frame toward and from the other frame, and also for adjusting one frame longitudinally with respect to the other frame so as to vary the lateral proximity of the rolls of one series with respect to the rolls of the other series.

A pair of feed rolls are usually provided at the forward end of a straightening machine, and an additional feature of the present improvement is to provide means for adjusting the straightening rolls without interfering with the adjustment of the feed rolls.

The invention is illustrated in the accompanying drawings, forming part hereof, in which—

Figure 1 is a side elevation of the straightening machine;

Fig. 2, a rear end elevation of the same;

Fig. 3, an elevation section of the same, looking forward on line 3—3, Fig. 1;

Fig. 4, a lower end view of a portion of the machine, as on line 4—4, Figs. 2 and 3;

Fig. 5, a fragmentary lower end view of the forward portion of the machine, with the gear wheels omitted;

Fig. 6, a transverse section of the machine, looking upward, as on line 5—5, Figs. 2 and 3;

Fig. 7, an enlargement of the forward portion of the same, with parts broken away to show interior details; and

Fig. 8, an enlargement of the rear portion of the same, showing a part broken away to show interior details.

Similar numerals refer to similar parts throughout the drawings.

The machine may include a base 9, on which is mounted a stationary journal frame 10 comprising a lower longitudinal bearing bracket 10, an upper longitudinal bracket 11, and upright connecting channels 12, with which is associated an adjustable journal frame, comprising a lower longitudinal bearing plate 13, an upper longitudinal bearing plate 13', and upright connecting bars 14.

Bearings 15 are provided in the longitudinal bearing brackets for journals 16 on the ends of one series of rollers 17, and bearings 15' are provided in the longitudinal bearing plates for journals 16' on the ends of another series of cooperating rollers 17'.

A beveled gear 18 is secured on the lower end of each roller journal 16, which meshes with a corresponding beveled gear 19 secured on a longitudinal shaft 20 journaled in bearings 21 and 21' mounted on the lower bearing bracket 10; upon the rear end of which shaft is secured a beveled gear 22 meshing with a beveled gear 23 secured on one end of a drive shaft 24, which shaft is journaled in a bearing 25 and has a pulley wheel 26 secured thereon, by means of which power is communicated to the machine.

A pair of feed rolls 27 and 27' is journaled in the upper and lower bearing brackets at the forward end of the machine, and upon protruding ends of their lower journals 28 and 28' are secured intermeshing gear wheels 29 and 29' for operating the feed rolls in unison; and a beveled gear 18' is also secured on the lower end of one of the journals 28, below the gear wheel 29, which meshes with a beveled gear 19' secured to the forward end of the shaft 20, by means of which the feed rolls are operated.

A gear wheel 30 is secured on the protruding lower end of each journal 16', and an idle gear wheel 31, meshing with each pair of adjacent gear wheels 30, is journaled upon the head 32 of a bolt 33 secured to the lower bearing plate 13, by means of which

all the straightening rolls 17' are operated in unison.

An idle gear wheel 31' is mounted upon the head 32' of a bolt 33' adjustably secured to the forward end of the lower bearing bracket 10; which gear wheel always meshes with the gear wheel on the lower end of the driven feed roll 27' and may be adjusted to mesh with the gear wheel 30 secured to the forward straightening roll 17, by means of which the power is communicated to the gearing which operates the straightening rolls 17'.

The bearing brackets 10 and 11 are provided with lateral extensions 10' and 11', the rear edges 34 of which are preferably beveled to form a socket 35 for receiving a toe 36 formed on the rear end of the bearing plates 13 and 13'; and each extension 10' and 11' is also provided with a pair of laterally extending ears 37, between which is entered a tongue 38 extending forward from the outer side of the front end of each bearing plate 13 and 13'. One ear 37 is provided with a free bore 39 and the other ear is provided with a tapped bore 39', and the intervening tongue 38 is provided with an enlarged opening 40; through which bores and opening a cap screw 41 is entered for clamping the tongue between the ears for securing the parts together.

The bearing brackets 10 and 11 are also each provided with a pair of ears 37' extending laterally from their forward ends, between which is entered a tongue 38' extending rearward from the inner side of the rear end of each bearing plate 13 and 13'. One ear 37' is provided with a free bore 39 and the other ear is provided with a tapped bore 39' and the intervening tongue is provided with an enlarged opening 40; through which bores and openings a cap screw 41 is entered for clamping the tongue between the ears for securing the parts together.

The enlarged openings 40 are wider than the diameter of the shanks 41' of the cap screws, so as to permit a lateral adjustment of either one or both ends of the bearing plates 13 and 13' with reference to the bearing brackets 10 and 11; and the openings are also elongated longitudinally, so as to permit a longitudinal adjustment of the bearing plates 13 and 13' with reference to the bearing brackets 10 and 11; by which means the rolls of each series may be adjusted toward and from each other, either in a

parallel or in an inclined relation, and they may also be adjusted longitudinally with reference to each other, so as to vary the proximity of the rolls of one series to the rolls of the other series, thereby facilitating the flattening and straightening of an expanded sheet by varying the depth and length of the reverse bends made therein by the cooperating series of rolls.

The opening 42 through which the shank of the bolt upon the head of which the idle gear is journaled, is elongated in the arc of a circle concentric with the gear wheel 29', so that the idle gear may be adjusted to properly mesh with the forward gear wheel 30, to conform to an adjustment of the bearing plates 13 and 13' and the rolls 17 and 17' journaled therein, while remaining in mesh with the gear wheel 29'. The journals 28' for one of the feed rolls 27' are preferably provided with a half box 43 bearing against a compression spring 44 held in position by a plug screw 45 to maintain a yielding pressure of the roll 27' toward the roll 27 for properly feeding sheets from an expanding machine to the straightening machine.

I claim:

1. A sheet metal straightening machine including two bearing frames, a series of rolls in each frame cooperating one with the other, and means for adjusting either one or both ends of a frame toward or from the other frame and also adjusting one frame longitudinally with reference to the other frame.

2. A sheet metal straightening machine including two bearing frames, a series of straightening rolls in each frame cooperating one with the other, and a pair of feed rolls in the end of one of the frames, and means for adjusting the other frame with reference to the one frame.

3. A sheet metal straightening machine including two bearing frames, a series of straightening rolls in each frame cooperating one with the other, a pair of feed rolls in one end of one of the frames, and means for adjusting the other frame with reference to the one frame, a chain of gears for operating all the rolls in the one frame, another chain of gears for operating the rolls in the other frame, and an adjustable gear wheel intervening between the two chains of gears for operating one from the other.

GEORGE W. LENTZ.
